UNITED STATES PATENT OFFICE.

WILLARD C. JAMES, OF LOS ANGELES, CALIFORNIA.

COMBINED COUCH AND BATH-TUB.

1,077,199.

Specification of Letters Patent.

Patented Oct. 28, 1913.

Application filed August 2, 1906. Serial No. 328,974.

To all whom it may concern:

Be it known that I, WILLARD C. JAMES, a citizen of the United States, residing at Los Angeles, in the county of Los Angeles and State of California, have invented a new and useful Combined Couch and Bath-Tub, of which the following is a specification.

It is of the objects of this invention to provide an article of furniture embodying the conveniences of a couch or bed, a bath-tub, commode, and toilet appliances, each of which may be used separately and independently of the other, and in which the presence of the bath and toilet appliances will be concealed when the furniture is in position for use as a couch or bed.

Other objects and advantages may appear from the subjoined detailed description.

The accompanying drawings illustrate the invention.

Figure 1 is a view of the article of furniture closed for use as a bed or couch. Fig. 2 is a view of the same article of furniture opened to give access to the bath, toilet, and commode. Fig. 3 is a fragmental detail showing the connection of the lid with the box by a shiftable hinge. Fig. 4 is a detail showing the construction at the front-right-hand corner in Fig. 2. Fig. 5 is a plan detail of the front left corner, the front closed and the lid raised.

1 in a general way designates a box having a floor 2, end walls 3, 4, back wall 5, front wall 6, and lid 7. The floor 2 does not come flush with the front ends of the end walls, but terminates rearward therefrom a distance approximately equal to the thickness of the front wall 6, and said front wall is hinged to the front edge of the floor 2 of the box, and its ends 71 are beveled to fit the ends 8 of the end walls 3 and 4 which are mitered to fit the beveled ends of the front wall 6 when the same is brought up to close the front side of the box.

9 is a catch to hold the front wall of the box in upright position for closing the same.

10 designates hinges by which the front wall 6 is hinged to the floor 2.

50 11 designates a bath-tub in the box 1.

12 is a rim inside the box at the level of the bath-tub to close over the space between the bath-tub and the walls of the box. The bath-tub is provided with a sloping or slanting head 13 as in the usual construction, and

14 designates the space underneath said sloping portion between the same and the head end of the box. 15 is a shelf in said space to receive a blacking-brush or other appliances.

16 is a receptacle between the foot end wall 4 of the box and the foot of the bath-tub, the same being adapted to receive towels, wash-cloths, and the like. The lid 7 may be upholstered as at 17 to form a couch or bed, and the lid is preferably hinged to the end walls of the box by shifting hinges 18 shown in detail in Fig. 3, which are constructed to shift the lid to bring the rear edge 19 and the upholstered surface 20 approximately flush with the rear edge of the box when the lid is in closed and open positions respectively.

21 is a commode drawer forming a receptacle 22 in which a commode jar 23 may be placed.

24 is a perforated seat, and 25 a cover therefor hinged at 26 to the commode drawer and adapted to be closed down upon the perforated seat 24 so as to cover the perforation when the commode drawer is slid into the receptacle 27 formed in the end of the box at the foot of the bath-tub to receive the commode drawer.

The wall 28 of the receptacle 16 forms a closure for the front of the commode drawer when said drawer is pushed into the receptacle 27. The lid 7 may be provided with a towel-rack 29, a mirror 30, and a swinging soap-dish 31, so that when the lid 7 is raised the person using the bath will have appliances at hand for performing his bath and toilet.

32 is a strip of carpet on the inside of the hinged front wall of the box to serve as a mat for the foot-rest. When the front wall is opened down to the floor it forms a protection for the carpet or other floor covering.

The bath-tub may be supplied with water through any suitable plumbing connections.

33 designate the usual bibs inside the bath-tub. Said plumbing connections will be understood by anyone skilled in the art and are therefore not illustrated in detail herein.

34 is a lid for the receptacle 16.

In practical use, when the article is closed as indicated in Fig. 1, the same being appropriately upholstered, forms an attractive couch which may be used as a bed as oc-

casion demands. When it is desired to take a bath, the lid 7 may be raised and the front wall lowered, whereupon the bath may be taken with the usual convenience; the towels 5 and other appliances being accessible when the lid and front wall are laid open. To use the commode, the commode drawer will be drawn out and its lid 25 raised. To return the article to the condition of a couch the 10 box will be closed in the usual way by reversing the operation just described. When the lid is closed the towel-rack with its towels, not shown, together with the mirror and swinging soap-dish, are stored out of the 15 way inside the bath-tub. The lid may be shiftably hinged by means of a plate 35 fastened to the rear edge of the lid, and two links 36, 37, each pivoted at one end to different points on the plate and at other points 20 on the end wall of the box. 38 is a spring for one of the links. The link 37 is pivoted to the end of the box by pivot 39 and to the lid by pivot 40, and the link 36 is pivoted to the box by pivot 41 and to the 25 lid by pivot 42. The pivot 40 may be located equidistant from the inner face and the rear edge of the lid, and the pivot 42 is preferably located at a like distance from the inner face of the lid. The pivot 39 is 30 preferably located vertically below the middle of the lid when said lid is raised, and the pivot 41 is preferably located at a point below the top of the box equal to the distance at which the pivot 39 is located from 35 the rear of the box. By this construction, when the lid is lowered from the position shown in Fig. 3, the links operate to carry the rear edge of the lid backward as the lid closes without throwing the rear corner of the 40 lid back from the vertical line drawn from the rear of the box. By this means the box-lid when closed and when open will stand flush with the rear of the box. The rear of the box may be with or without a wall. In 45 Fig. 3 the back wall for the box is shown as formed by the wall of a room. The spring 38 tends to hold the link 37 forward, thus tending to hold the lid open. The box may be covered or upholstered in any way, and 50 said covering 43 may be folded on the beveled ends 8 and 71 of the end walls and the lid. By means of the shifting hinge the inside wall of the lid when raised may be brought flush with the inside of the back 55 of the tub so that any drip from the lid will fall directly into the tub and not on the rim thereof. This result is effected by pivoting the link 37 to a lid, said lid being of definite thickness, the pivot being near the face 60 thereof that is inverted when the lid is closed and also pivoting the link to the box at a distance from the rear thereof, equal to half the thickness of the lid, and pivoting the other link to the lid above the pivot of 65 the first mentioned link 37 when the lid

is upright and pivoting the other end of said link 36 to the box forwardly, as seen in Fig. 3.

What I claim is:—

1. A bath tub, a box inclosing the bath 70 tub, the bottom of the box being adapted to rest flat upon the floor, the front side of said box being hinged to swing down flat upon the floor and form a protection for the floor, and the top of the box being hinged to swing 75 upwardly and form a holder for toilet articles, the front face of the top when in its vertical position being in position to drain into the bath tub.

2. A bath tub, a box inclosing the bath 80 tub, the bottom of the box being adapted to rest flat upon the floor, the front side of the box being hinged to the bottom of the box and adapted to fold flat upon the floor, and carpet covering the inner face of said front 85 side and overlapping the edge of the bottom of the box to form a protection for the floor.

3. A bath tub having a sloping head, a 90 box inclosing the bath tub and having a front side adapted to swing flat upon the floor, a shelf in the box under the sloping head, and a lid for the box for covering the bath tub, said hinged front giving access to the shelf and also forming a protection for 95 the floor.

4. A bath tub provided with a sloping head, a box inclosing the bath tub, the front side of the box being hinged to swing flat upon the floor and to give access to the 100 space beneath the sloping head, and a lid for covering the bath tub.

5. A bath-tub, a box inclosing said bath-tub, the end walls of said box extending forwardly beyond the edge of the floor of the 105 box and being beveled at their front edges, the front wall of said box being hinged to said floor of said box and adapted to swing flat upon the floor of the apartment and beveled at its ends to fit the beveled ends of the end walls of the box, and means for holding the front wall of the box upright in closed position.

6. A combination article of furniture comprising a bath tub, a box inclosing the same 115 and provided with a lid spaced apart from the end of the bath tub and extending to the top of the bath tub, a vertical partition in said space, a drawer in said space upon one side of the partition adapted to be drawn 120 out of the same through the end wall of the box and provided with a chamber and a perforated seat, a cover for the space upon the other side of the partition, and a cover 125 for the perforated seat.

7. A bath-tub, a box inclosing the same and provided with an upholstered lid, and a shifting hinge shiftably hinging the upholstered lid to the body of the box to bring 130 the edge of the lid and top of the lid flush

with the edge of the box in closed and open position, respectively, the rear wall of the tub being spaced from the rear wall of the box to accommodate the lid when raised so 5 that the front face of the lid will drain into the bath tub.

8. The combination with a bath-tub, of a box provided with a lid of determined thickness and a shifting hinge connecting 10 said lid with the body of the box and adapted to shift the lid to bring the edge and the top thereof approximately flush with the back of the box when the lid is in its closed and its open positions respectively; so that 15 when the lid is elevated its front face will drain into the bath tub; said lid comprising

a link pivoted to the inside edge of the lid and also pivoted to the box at a distance from the rear side thereof, equal to half the thickness of the lid, and another link pivoted to the lid above the pivot when the lid is upright and pivoted to the box in front of said upright lid, and a spring fastened to the box and to the first named link to draw said link forward. 20

In testimony whereof, I have hereunto set my hand at Los Angeles, California this 27th day of July 1906.

WILLARD C. JAMES.
